UNITED STATES PATENT OFFICE.

HENRY R. MYERS, OF COVINGTON, KENTUCKY.

DESIGN FOR A SEALING DEVICE.

SPECIFICATION forming part of Design No. 30,776, dated May 16, 1899.

Application filed April 6, 1899. Serial No. 712,029. Term of patent 14 years.

To all whom it may concern:

Be it known that I, HENRY R. MYERS, a citizen of the United States, and a resident of Covington, in the county of Kenton and State of Kentucky, have invented and produced a certain new and useful Design for Sealing Devices, of which the following is a specification, reference being had to the accompanying drawings, forming part of the same, in which—

Figure 1 is a perspective view of a sealing device, exhibiting my new design. Fig. 2 is an upper face view of the same. Fig. 3 is a rear end view of the same, and Fig. 4 is an edge view of the same.

This seal, which I have invented and produced in the design exhibited, consists in a thin metal plate with a connecting-plate *c*, substantially rectangular in face outline, and two projecting portions *p* of a width substantially even with that of the connecting-plate, the ends of which are bounded by lines proceeding from the side lines of said portions *p* and gradually approaching each other till they meet at a point substantially midway between the side edges of said plates *p*, but farther from the junction of said plates and

the so-called "connecting-plate" *c* than are the points where said lines begin.

This design has useful as well as ornamental features; but the main features of the design are the three parts—plate *c*, a rectangular portion with substantially straight sides, and two plates *p*, projecting from opposite sides of plate *c*, of a width substantially even with that of plate *c* and substantially straight sides, their ends being bounded by lines proceeding from the respective sides of plate *p* and gradually approaching each other till they meet at a point about midway between those sides, but farther from the junction of plates *c* and *p* than are the points where said lines begin.

What I claim as my invention, and desire to secure by Letters Patent, is—

The design for a sealing device substantially as herein shown and described.

Signed at Covington, in the county of Kenton and State of Kentucky, this 31st day of March, A. D. 1899.

HENRY R. MYERS.
